Packaging Corp., Cambridge, Mass., a corporation of
Massachusetts

Filed July 21, 1966, Ser. No. 3,158

Term of patent 14 years

(Cl. D61—1)

FIG. 4

FIG. 5

FIG. 1 is a top plan view of a flange for a tape reel, showing one form of my new design wherein there are two areas of contrasting texture.

FIG. 2 is an enlarged fragmentary cross-sectional view taken on line 2—2 in FIG. 1;

FIG. 3 is an enlarged fragmentary cross-sectional view taken on line 3—3 of FIG. 1;

FIG. 4 is a top plan view of a flange for a tape reel, showing a second form of my new design wherein there are three areas of contrasting texture; and

FIG. 5 is an enlarged fragmentary cross-sectional view taken on line 5—5 in FIG. 4.

The dominant features of my new design are shown in solid lines in the drawing. The broken line fragmentary showing of a cylindrical reel hub in FIGS. 2 and 3 is for illustrative purposes only.

Stippling is employed to illustrate contrast of surface texture.

I claim:

The ornamental design for a flange for a tape reel, as shown and described.
